CLAIM

The ornamental design for a support strap bracket, as shown and described.

DESCRIPTION

FIG. 1 is a bottom perspective view of a support strap bracket showing my new design;

FIG. 2 is a top plan view thereof;

FIG. 3 is a side elevational view thereof, the side opposite being a mirror image;

FIG. 4 is a bottom plan view thereof;

FIG. 5 is a front elevational view thereof; and

FIG. 6 is a rear elevational view thereof.
